CLAIM

The ornamental design for a butterfly toy, as shown and described.

DESCRIPTION

FIG. 1 is a top front perspective view of a butterfly toy showing my new design;

FIG. 2 is a bottom rear perspective view thereof;

FIG. 3 is a front elevation view thereof, the rear elevation view being a mirror image thereof;

FIG. 4 is a top plan view thereof;

FIG. 5 is a bottom plan view thereof;

FIG. 6 is a right-side elevation view thereof, the left-side elevation view thereof being a mirror image thereof;

FIG. 7 is a front perspective view of the center body of the butterfly toy shown with wings omitted for clarity of illustration; and,

FIG. 8 is an exploded front perspective view of the left wing of the butterfly toy, shown with the center body omitted for clarity of illustration.

1 Claim, 8 Drawing Sheets
